ADJUSTABLE OUTLET BOX SUPPORT

Ottomus G. Dedge, Alma, Ga.

Application January 11, 1944, Serial No. 517,845

3 Claims. (Cl. 220—3.9)

1

This invention relates to an improved adjustable outlet box constructed along general lines evidenced in prior types of adjustable boxes of which there are many both on the market and covered in prior patents classified in the subdivision to which the instant invention belongs.

It is a matter of common knowledge that in fastening outlet boxes to accommodate electricity conductors, switches, fixtures and the like, the plasterers who generally follow up the electric wiring men in building construction work are often confronted with the difficulty of evening up or rendering flush the plaster with the outer edge of the box. This often necessitates blocking the box out or adjusting it in relation to the wall with a view toward securing the desired flush relationship of parts. As intimated I am aware that in view of this, adjustable boxes are now provided to compensate for such difficulties.

My primary aim is to generally improve upon such prior devices as are known to me, this by providing an outlet box which is characterized by distinctive refinements and structural improvements which, in my judgment, render my structure more aptly suitable for the purposes intended.

The primary phase of the instant invention has to do with the provision of brackets at substantially diametrically opposite points, these arms having their inner ends fashioned to function in channel-like keyways, there being swivelly mounted adjusting screws located in said keyways and connected with the arms to regulate and retain the position of said arms in relation to other parts.

Other features and advantages of the invention will become more readily apparent from the following description and the accompanying illustrative drawings.

In the drawings, wherein like numerals are employed to designate like parts throughout the same—

Figure 1 is a plan view of an outlet box embodying the improvements of the instant invention.

Figure 2 is a central longitudinal sectional view through the arrangement seen in Figure 1.

Figure 3 is a side elevation, this showing the bracket or hanger arms assuming an overlapped folded out-of-the-way position.

2

Figure 4 is a view, centrally in section, showing how the bracket arms or hangers are bent for special anchorage purposes on a beam or like inwardly of the ceiling or wall.

5 Figure 5 is a sectional view showing how the projectible and retractible spurs or detents are employed for temporary setting of the box in the ceiling or wall construction.

Figure 6 is a perspective view of one of the 10 bracket arms.

Figure 7 is a section showing the formation of the inner adjustable end of the bracket arm and groove or keyway in which it functions.

It is to be understood that I am not interested 15 in the particular or special construction of the box in general, but only in the special improvements which I have devised. Thus, the outlet box is generally denoted by the numeral 8 and is provided with the usual parts and knock-out 20 plugs 9. One improvement which I have in mind is the provision of temporary setting and anchoring elements. These are denoted by the numerals 10. They are struck-out fingers or tongues whose free ends 11 are laterally bent to provide spurs 25 such as are designed to be projected by a blow from a hammer or a hammer against a tongue to fasten the same in the ceiling as shown for example in Figure 2. The purpose of this will be brought out later.

30 The second characteristic in the box construction is the provision at diametrically opposite points of indentations defining channel-like keyways 12. Spanning the bottom of each keyway there is a web forming what may be conveniently 35 called a lug 13. Swivelly mounted in this lug and occupying position centrally of the keyway is a threaded adjusting screw whose headed end 14 is swivelly mounted in the lug and whose opposite end 15 projects beyond the adjacent surface of 40 the box to serve a purpose to be subsequently clarified.

It will be noticed that the preferred form of the hanger or bracket arms is that seen in Figure 6. That is to say, each arm is a flat strap of metal or 45 equivalent material of suitable rigidity and length and dimension. At the inner end there is a struck-up segmental or substantially arcuate lip 17 which is shaped to fit and slide in the keyway 12. Adjacent this there is a screw-threaded hole 50 18 which serves to accommodate the shank of the

adjusting and feed screw 15. At the outer free end the arm is provided with appropriate fastener or nail holes 19. It follows that at diametrically opposite points the box is provided with channel-like keyways having swivelly mounted feed screws therein, the feed screws serving to accommodate the adjacent inner ends of the bracket arms. These arms being on the screws are provided with lip-like detents 17 and can serve in several ways. Ordinarily, the bracket arms are simply adjusted to hang or rest against the inner surface of the ceiling or wall A shown for example in dotted lines in Figure 4. This will be the same position as occupied by the then outstanding arms 16 in full lines in Figure 2.

It can be seen that it is often necessary when using a wooden panel wall or ceiling that the hole for the outlet box is cut-out and sometimes the box has to be slipped into place through the hole. For this reason it will be noticed that the projected ends of the screws 15 in Figure 3 permits the arms to be swung in to overlapping relationship as seen in Figure 3.

In this position the arms are retracted and folded upon each other to an out-of-the-way position and the entire box, including the then folded arms can be slipped up through the hole and anchored in place. Then, when the arms are thrown out to project beyond the peripheral or rim portion of the box it is necessary to draw them down against the ceiling as shown in dotted lines in Figure 4. Of course, at this time it is necessary that the box be stationary in relation to the then adjustable arms. This is where the aforementioned retaining spurs 11 come into the picture. As shown for example in Figure 5, these spurs are driven out through their adjacent slots and anchored in place. This temporarily fastens the box to the ceiling and makes it stationary. Consequently, by turning a screw-driver in the headed ends of the swivel feed screws 15 the hanger or bracket arms can be fed down into place in relation to the then stationary box.

When it is necessary to attach the hanger arms to a horizontal or vertical stud such as shown at B in Figure 4 the intermediate portion of the arm is bent laterally to extend diagonally as at 20 and the free end is bent at the desired angle in relation thereto as indicated at 21. This makes for proper angulation of the bent portions of the hanger arms to adapt the same for use as brought out in Figure 4. It would be quite possible to attach these arms to the setting and then screw the box into place. However, experience of electricians and wiring men will serve as the answer to this.

By way of summation, one phase of novelty has to do with the integral webs 13 which span the normal lower ends of the coating channels 12, said webs serving to function as lugs and providing convenient means to swivelly mount the feed screws 15, that is, to position the feed screws in the channels in proper centralized and longitudinally extending relationship. Novelty is also predicated upon the idea of fashioning the inner ends of the hanger arms into arcuate formations and to also provide correspondingly curved reinforcing lips, the curved ends and lips fitting nicely into the correspondingly curved channels, whereby to provide a convenient and nicely adaptable arrangement in which the lip-equipped arcuate ends of the arms are adjusted in the accommodation channels.

In addition to the above, the arrangement depicted in dotted lines in Figure 1 and in full lines

5 in Figure 3, is stressed. By this, I mean that the arms 16 are such in length that they can be brought into overlapping relationship when folded as shown. Each arm, when folded, has the outer flanged end 17 substantially flush with a perimeter rim or wall of the shell and the opposite free swingable end of the arm terminates short of the opposed wall portion of the rim, or to put it otherwise, each arm is of a length to terminate within the outer peripheral limits of the flat top wall of the shell.

10 It is thought that persons skilled in the art to which the invention relates will be able to obtain a clear understanding of the invention after 15 considering the description in connection with the drawings. Therefore, a more lengthy description is regarded as unnecessary.

20 Minor changes in the shape, size and arrangement of details coming within the field of invention claimed may be resorted to in actual practice, if desired.

Having described the invention, what is claimed as new is:

25 1. An outlet box including a shell having substantially diametrically opposite channels constituting keyways, perforated lugs in said keyways, feed-screws in said keyways mounted for rotation through said lugs, a pair of hanger arms having their inner ends formed with transversely ar- 30 cuate end edges and extending into said keyways and provided with screw-threaded holes, the feed-screws being threaded through said holes, and the inner ends of said arms being formed with arcuate upstanding lips along their end edges to bear against walls of the keyways and 35 guide movement of the arms through the keyways.

2. An outlet box including a hollow shell pro- 40 vided with a substantially flat wall and a surrounding marginal wall, said marginal wall being provided with diametrically opposite channels constituting keyways, said keyways having therein perforated lugs, said lugs projecting into corresponding ends of the keyways, feed screws 45 located for rotation in said keyways and swivelly mounted in said lugs, screw-threaded end portions of said feed-screws projecting through and beyond those ends of said channels adjacent the aforesaid flat wall of the shell, a pair of hanger arms, said arms being of lengths, when folded and not in use, to terminate at opposite ends within the perimeter limits of said flat wall, said arms being disposed when folded in overlapping relationship, and having their outer ends provided with screw-threaded holes, said feed-screws being 50 threaded into and through said holes.

3. An outlet box including a hollow shell pro- 55 vided with a substantially flat wall and a laterally disposed and surrounding marginal wall, said marginal wall being provided with oppositely located open-ended channels constituting keyways; said marginal wall having perforated lugs, said lugs projecting into corresponding ends of said keyways, feed-screws located for rotation in said keyways and swivelly mounted in said lugs, cor- 60 responding screw-threaded end portions of said feed-screws projecting through and beyond the ends of said channels adjacent to the aforesaid flat wall of the shell, a pair of hanger arms, each arm being of a length to terminate inwardly of the outer perimeter of said flat wall, said arms being disposed in overlapping relationship, and having their outer ends provided with screw-threaded holes, said feed-screws being threaded into and through said holes, each hanger arm 65 comprising a flat, rectangular strip provided at

its inner end with nail holes for attachment and anchorage purposes, the outer end of each arm being provided with a lateral substantially semi-circular lip, said lip projecting laterally beyond one flat surface of the arm.
